UNITED STATES PATENT OFFICE.

EDWARD TOWE, OF ROCHESTER, NEW YORK.

CONCRETE-INSERT.

1,359,290.

Specification of Letters Patent. Patented Nov. 16, 1920.

Application filed January 26, 1920. Serial No. 354,209.

To all whom it may concern:

Be it known that I, EDWARD TOWE, citizen of the United States, residing at Rochester, in the county of Monroe and State of New York, have invented certain new and useful Improvements in Concrete-Inserts, of which the following is a specification.

The object of this invention is to provide a new and improved form of concrete insert and means whereby the insert may be temporarily but securely fastened to the wooden framework that forms the mold for the concrete.

This and other objects of this invention will be fully illustrated in the drawings, described in the specification and pointed out in the claims at the end thereof.

In the accompanying drawings:

Figure 1 is a perspective view of the insert as it is being placed and fastened to the bottom of the mold for the concrete.

Fig. 2 is a perspective view of the jig for locating and driving the nails which hold the insert in place on the bottom of the mold.

Fig. 3 is a horizontal section of one of the inserts shown in place on the bottom of the mold, the nails for holding the insert in place being illustrated in the position which they occupy before they engage the insert to lock it in place on the bottom of the mold, the section through the mold being taken on the line 3^x-3^x of Fig. 6.

Fig. 4 is a horizontal section of the same mold after it has been turned so as to engage the nails in the bottom of the mold to hold the insert securely in place thereon.

Fig. 5 is a vertical sectional view of one of the inserts as it will appear after the concrete has been poured around it so as to embed the insert therein, the section being taken on the line 5^x-5^x of Fig. 4.

Fig. 6 is a vertical section of the insert after the concrete has hardened and the bottom of the mold has been removed from it, the section being taken on the same line as the section of the insert shown in Fig. 5.

Fig. 7 is a vertical section of the insert similar to the sections shown in Figs. 5 and 6, showing an anchor plate supported therein.

Fig. 8 is a top plan view of the anchor plate used in connection with the insert.

In the several figures of the drawings, like reference numerals indicate like parts.

The insert forming the subject matter of

this invention comprises the inverted conical shell 1 which is closed at the top as is shown at 2 and is provided with the opening 3 at the bottom thereof. The opening 60 3 is elliptical in outline as shown in Figs. 1, 3 and 4, and is smaller than the bottom of the inside of the conical shell so that an annular flange 4 is formed at the bottom of the shell which surrounds the opening 3. 65 The flange 4 is cut away at diametrically opposite points and in line with the long axis of the elliptical opening 3 to form the notches 5 and 6 therein for a purpose that will presently appear.

When a concrete floor is laid, a false work is first erected covered with boards or other suitable material to form a mold into which the concrete is poured. The concrete is supported by this false work, especially the 70 bottom of the mold, until it has obtained sufficient hardness and stiffness so that the false work can be removed, leaving the concrete in place to support itself.

In order to facilitate the supporting of hangers from a ceiling formed of concrete in the manner above described, suitable means must be embedded in the concrete to which hangers can be attached after the concrete has set and is strong enough to support 80 85 them.

The inverted conical shell 1 is used for the purpose of supplying such means for supporting suitable hangers from ceilings. It is cast in one piece and is adapted to be embedded in the concrete by pouring the concrete around it while the floor or ceiling is being laid so that after the concrete has hardened and has attained sufficient strength, it is held firmly in place and forms an ideal 90 95 support in the ceiling to which the hanger can be attached.

For the purpose of fastening and locating the insert on the false work that forms the mold for the concrete ceiling, the opening 100 in the bottom of the shell 1 is outlined so that it can be locked to a pair of nails which have previously been driven into the bottom of the mold and properly located and lined up thereon on previously determined points 105 decided upon according to the requirements in each specific case.

The points at which each of the inserts is to be located in the ceiling is marked on the bottom of the mold preferably by means 110 of chalk marks such as are indicated by the lines 7 and 8 in Figs. 1, 2, 3 and 4, the in-

terse ting point of these lines representing the point at which the insert is to be centered and fastened to the bottom of the mold.

5 In order to properly locate the nails that are to hold the insert in place at this point, the jig 9 is used. This jig comprises a circular disk which is provided with an opening 10 in the center and has a portion of 10 the periphery cut away at diametrically opposite points as indicated at 11 and 12 in Fig. 2. Each of the cut-away portions 11 and 12 forms a small notch 13 at diametrically opposite points on the periphery of 15 the disk. The jig is placed on the bottom of the mold so that the intersecting point of the lines 7 and 8 is centered in the opening 10 of the jig. A pair of nails 14 and 15 is then driven through the notches 13 into 20 the bottom of the mold until the heads of these nails strike the top edge of the jig. The nails 14 and 15 thus driven into the mold are thus properly spaced apart by the notches in the jig and the distance which 25 they are allowed to project out from the bottom of the mold is gaged by the thickness of the jig and corresponds with the thickness of the flange 4 of the insert.

After the nails for fastening the insert 30 have thus been properly located on the bottom of the mold, the jig is removed and the insert is placed over the nails in such a way that the nails 14 and 15 enter the notches 5 and 6 in the insert so as to allow 35 these nails to project into the inside of the shell of the insert with the heads of the nails projecting above the annular flange 4 thereof. The oblong or elliptical opening 3 in the bottom of the insert admits the insertion 40 of the nails without any obstruction thereto and when thus inserted, allows the rotation of the shell 1 which brings the nails in line with the short axis of the elliptical opening. In doing so, the sides of the 45 opening are brought close to the sides of the nails and the heads thereof overhang the edges of the flanges 4. In order to allow the shanks of the nails to center themselves at the narrowest point of the opening 3 a 50 pair of notches 16 and 17 are provided in the flanges 4 at this point and when the nails 14 and 15 are in line with these notches they are adapted to spring into them and the shell 1 will be held in place on the nails. 55 The overhanging portion of the heads of the nails, together with the close fitting of the shanks of the nails to the sides of the flanges 4, operates to securely fasten the insert to the bottom of the mold of the ceiling and the concrete may then be poured around it without danger of moving the inserts during the pouring operation.

When the concrete has set and the concrete is strong enough to support itself, the 60 false work, including the bottom of the mold

to which the insert had been attached, is removed. In doing this, the nails that held the insert in place on the mold, are pulled out from the wood and as soon as the wood is removed these nails will fall out from 70 the insert. The bottom of the insert will then be free and unobstructed so that the anchor plate 18 can be inserted therein and suitable hangers suspended therefrom.

The anchor plate 18 consists of a plate 75 having a slot extending from one side thereof of about three-quarters of the way across the plate. Surrounding this slot is the flange 19. The plate 18 is intended to hold a bolt or other support and the flange on 80 the plate is intended to engage with the head of the bolt or the nut and prevent it from turning on the plate and its slot. The plate 18 is inserted into the insert by first engaging the bolt with the plate and then 85 passing the plate edgewise through the notches 6 and 7 in the manner shown in dotted lines in Fig. 6 until it is on the inside of the insert. The plate is then turned to a horizontal position and allowed to rest 90 on the flanges 4.

The flange 4 is provided with the serrations 20 as indicated in Figs. 3 to 7, inclusive, and the plate 18 is provided with corresponding teeth at the bottom side thereof 95 to engage these serrations in any desired position in which the plate is to rest in the insert. By lifting the plate, the position may be shifted to any other position in which it will be held in place as soon as the 100 plate is again allowed to rest on the flange 4. In this way the slot can be made to point in any direction.

The bolt can be placed at any place along the slot in the plate which means that it 105 can be located in the center of the shell as well as at any point between the center and the periphery of the plate.

The conical shell 1 is held best in the concrete when its sides have an inclination of 110 about 20°.

I claim:

1. In a concrete insert, the combination of an inverted conical shell, said shell being open at the bottom and closed at the 115 top, said open bottom being provided with a pair of curved flanges, said curved flanges being eccentric to the opening in the bottom in said shell, a pair of notches located diametrically opposite each other in the bottom 120 and separating said flanges.

2. In a concrete insert, the combination of an inverted conical shell, said shell being closed at the top and having an elliptical opening at the bottom, a flange surrounding said opening, said flange having a pair of notches cut into it diametrically opposite each other and in line with the long axis of the elliptical opening.

3. In a concrete insert the combination 130

of a conical shell, a pair of curved flanges at one end of said shell extending inwardly thereof, said curved flanges being eccentric to the inside wall of said shell, an anchor plate adapted to be inserted between said flanges into the inside of said shell to be supported by said flanges, said shell being adapted to be passed over a pair of nails

with said flanges loosely embracing the nails, said shell being adapted to be turned 10 around the nails to have the heads of the nails project over said curved flanges in order to hold said shell in place thereby.

In testimony whereof I affix my signature.

EDWARD TOWE.
